L. D. LOVEKIN

SURFACE CONDENSER

Filed May 8, 1923

Fig. 1.

Fig. 2.

UNITED STATES PATENT OFFICE.

LUTHER D. LOVEKIN, OF ARDMORE, PENNSYLVANIA.

SURFACE CONDENSER.

Application filed May 8, 1923. Serial No. 637,443.

To all whom it may concern:

Be it known that I, LUTHER D. LOVEKIN, a citizen of the United States of America, and resident of Ardmore, county of Montgomery, State of Pennsylvania, have invented a certain new and useful Improvement in Surface Condensers, of which the following is a true and exact description, reference being had to the accompanying drawings, which form a part thereof.

My invention relates to surface condensers of the general kind described in my Patent 1,264,195 of April 30, 1918. The object of my invention is to provide for a better flow of steam through the cooling tubes and for the use of the cooling water in the most efficient manner.

The nature of my improvements will be best understood as described in connection with the drawing in which they are illustrated and in which—

Figure 1 is a cross sectional view of my improved condenser, and

Figure 2 a sectional elevation on the line 2—2 of Fig. 1.

A indicates the condenser shell having an opening at its top for the admission of steam indicated at A'. At each end of the shell are the heads for the cooling water indicated at B and C, the head C being divided into two chambers C' and C² by a partition C³, C⁴ indicating the opening into the head for the entrance of cooling water and C⁵ the opening into the head for the outflow of water. D is a group of cooling tubes extending through the shell and located in the upper section of the shell. This group of tubes has a generally arch-shaped form and is so disposed as to leave the steam spaces, indicated at F, F, between the sides of the arch shaped group of tubes and the walls of the shell. E and E' indicate two lateral groups of tubes located in the lower section of the shell and spaced from the wall of the shell by downwardly contracting steam passages indicated at F', F', the tops of these steam passages registering with the steam passages F, F, so that steam can flow freely along the sides of the shell. E² indicates a central group of cooling tubes located chiefly in the lower section of the shell, spaced from the upper group of tubes as indicated at G, and from the lateral groups by the vertical passages indicated at G', G². H, H, are rain plates located be-

tween the upper group of tubes and the lower lateral groups of tubes and H' is a rain plate preferably of curved form, as shown, located over the top of the central lower group of tubes and in such position as not to interfere with the steam space indicated at G. I is a casing extending up through the lower central group of tubes and formed with openings, indicated at I', I', etc., for the entrance of air. This casing I communicates with the chamber I² which is in communication with an air pump. J is a water seal surrounding the opening A² in the bottom of the shell A and J' is an opening into the chamber I² by which it is connected with the wet air pump which draws off the condensate and gases. The walls of the chamber I² extend down into the water seal, as indicated at K. In the construction illustrated, the water entering the chamber C² passes through the three lower groups of tubes to the chamber B and thence through the upper group of tubes indicated at D into the chamber C' and to exhaust.

The steam entering the shell through the opening A' passes, for the most part, through the cooling tubes D into the space indicated at G, but in my new construction a portion of the steam is permitted to flow freely past the upper group of tubes through the passages F, F, and into the converging passages F', F', from which the steam passes through the lateral tube groups indicated at E and E'. The air and uncondensable gases with some uncondensed steam ordinarily mixed with them, pass from the passages G' into the lower central tube group E² and into the casing I, from which they pass through the chamber I² to the air pump.

My condenser is designed so that the latent heat of the steam will, under the best conditions, be completely extracted in the tube groups D and E, E', leaving no work for the central lower group of tubes except the cooling of the air so as to condense it as much as possible and lessen the work on the air pump. It is advisable, however, that the central lower tube group E² should have more surface area than that merely required for the cooling of the air, as, under some conditions, uncondensed steam in small quantity will pass to this group.

Having now described my invention, what I claim as new and desire to secure by Letters Patent, is:

1. In a surface condenser comprising a shell having an opening at its top for the entrance of steam, and horizontal tubes extending through the shell for cooling water, the construction in which the tubes are disposed in groups, one extending across the upper part of the shell in such a way as to leave steam spaces between its sides and the side of the shell, two lateral groups of tubes located in the lower half of the shell with downwardly contracting steam spaces between the outer sides of said groups and the shell, and a central group of tubes located in the lower section of the shell between and spaced from the lateral groups in combination with rain plates located between the upper group and central lower group of tubes and between the upper group and the lower lateral groups whereby condensate from the upper tube group is directed into the spaces between the lateral and central lower tube groups, and with an air outlet opening into the lower central tube group.

2. In a surface condenser comprising a shell having an opening at its top for the entrance of steam, and horizontal tubes extending through the shell for cooling water, the construction in which the tubes are disposed in groups one extending across the upper part of the shell in such a way as to leave steam spaces between its sides and the side of the shell, two lateral groups of tubes located in the lower half of the shell with downwardly contracting steam spaces between the outer sides of said groups and the shell, and a central group of tubes located in the lower section of the shell between and spaced from the lateral groups, in combination with rain plates located between the upper group and central lower group of tubes and between the upper group and the lower lateral groups whereby condensate from the upper tube group is directed into the spaces between the lateral and central lower tube groups, with an air outlet opening into the lower central tube group and means for circulating water first through the three lower tube groups and then through the upper tube group.

LUTHER D. LOVEKIN.
